[57] CLAIM

The ornamental design for a paint brush and tool
keeper, as shown and described.

DESCRIPTION

FIG. 1 is an end elevational view of a paint brush and
tool keeper showing my new design, the opposite end
being a mirror image thereof;

FIG. 2 is a top plan view thereof;

FIG. 3 is a side elevational view, the opposite side being
a mirror image thereof; and

FIG. 4 is a bottom plan view.
